OUTDOOR BARBECUE STOVE

Charles C. Clausen, P.O. Box 296, San Ardo, Calif.

Filed June 28, 1965, Ser. No. 85,927

Term of patent 14 years

(Cl. D81—10)

FIG. 1 is a perspective view showing an outdoor barbecue stove of my design;

FIG. 2 is a top plan view of the outdoor barbecue stove of FIG. 1, at a reduced scale;

FIG. 3 is a side elevation view of the invention at a reduced scale, the grill being shown in elevated position; and

FIG. 4 is a front elevation view of an outdoor barbecue stove embodying my invention.

Portions of the article are shown broken away in FIG. 1 to more clearly disclose the contours of the affected areas.

I claim:

The ornamental design for an outdoor barbecue stove, as shown and described.
